UNITED STATES PATENT OFFICE.

ALBERT HUPP, OF WASHINGTON, DISTRICT OF COLUMBIA, ASSIGNOR TO HUPP AUTOMATIC MAIL EXCHANGE COMPANY, OF WASHINGTON, DISTRICT OF COLUMBIA, A CORPORATION OF DELAWARE.

RAILWAY MAIL-EXCHANGE APPARATUS.

1,243,606.

Specification of Letters Patent. Patented Oct. 16, 1917.

Application filed February 26, 1915. Serial No. 10,748.

To all whom it may concern:

Be it known that I, ALBERT HUPP, a citizen of the United States, and a resident of Washington, District of Columbia, have invented certain new and useful Improvements in Railway Mail-Exchange Apparatus, of which the following is a description.

This invention relates to mail exchange apparatus and more particularly to mechanism for automatically delivering mail bags from a car.

The object of the invention is to provide an improved mechanism of this character which will be capable of handling a large number of mail bags at one time and which will be simple and reliable in operation.

Other objects and the features of novelty will be apparent from the following description taken in connection with the accompanying drawings in which—

Figure 1 is a transverse section through a mail car having my invention applied thereto;

Fig. 2 is a side elevation of the delivery mechanism;

Fig. 3 is an enlarged side elevation of the lower part of one of the delivery chutes, a part of the side wall being broken away to disclose other parts;

Fig. 4 is a section on the line 4—4 of Fig. 3; and

Fig. 5 is a detail of the latching mechanism for the delivery chute bottom.

Referring to the drawings 10 indicates the body of a mail car which is provided with the opposite doorways 11 and 12.

Tracks 13 and 14 extend across the interior of the car and are secured to the sides thereof by means of suitable brackets 15.

The tracks 13 and 14 are also additionally supported by posts 16 which carry cross members 17, these cross members being secured to the upper sides of the tracks. A delivery chute 19 is provided with the supporting arms 20 extending rearwardly and upwardly therefrom as shown in Fig. 1.

The arms 20 carry wheels 21 which engage the tracks 13 and 14 and thus support the chute 19 so that it may be moved to and fro through the doorway 12.

A delivery chute 22 is arranged on the opposite side of the car and is provided with supporting arms 23 extending rearwardly and upwardly therefrom, these

arms having rollers 24 which also engage the tracks 13 and 14 and support the chute. From Fig. 2 it will be seen that the rollers 21 are on the opposite sides of the tracks 13 and 14 from the rollers 24 so that the chutes 19 and 22 may be moved to and fro independently without interference. Supported on the floor of the car, in suitable bearings 25 is a shaft 26 having upwardly projecting arms 27, the upper ends of these arms being connected with the chute 19 by means of the links 28. The sides of the chutes 19 and 22 are formed with two spaced plates 29 and 30, as shown in Fig. 4, and the arms 27 are arranged between these plates and concealed thereby. In Fig. 1 chute 19 is shown in the normal inoperative position on the inside of the car while the chute 22 is shown in full lines in the operative position for delivery of mail bags. The chute 22 is also shown in dotted lines in Fig. 1, within the car. The operating mechanism for the chutes 19 and 22 are identical and since the mechanism for the chute 22 is illustrated in detail a description of the same will now be given. The chute 22 is moved to and fro by means of arms 27 and links 28, as above described and the shafts 26 are rocked by means of downwardly extending arms 31 which project through the floor of the car and are connected with actuating mechanism 32. Any suitable actuating mechanism may be provided for the chutes 19 and 22 and an example of such mechanism is illustrated in my earlier application Serial No. 771,041, filed May 31, 1913.

The chutes 19 and 22 are provided with dumping bottoms 33, these bottoms being pivoted to the sides of the chutes at 34 and being adapted to swing downwardly to the position shown in Fig. 1. The bottoms 33 are provided with the side walls 35 having secured to the upper edges thereof bars 36, these bars coöperating with bars 37 arranged on the walls 29 for the purpose of limiting the downward movement of the bottoms. The bottoms 33 have secured thereto quadrants 38, which are turned under the bottoms 33, as indicated at 39 and secured thereto, and also secured to the sides 35, by suitable pins or bolts 40. The bolts 40 extend through the walls 29 of the chutes and curved slots 41 are provided in these walls to permit the movement of the pins 40 with

the bottoms when the latter swing to the open position. Each of the quadrants 38 is provided with a notch 42 and these notches are engaged by bolts 43 slidable in casings 44 secured to the walls 29. The bolts 43 are moved to and fro into and out of engagement with the notches 42 by means of levers 45 which are pivoted to the casings 44 and connected with levers 46 by means of links 47. The levers 46 are pivoted at 48 to the walls 29 and 30 and have their upper ends connected with the arms 27 by means of telescopic links. These telescopic links comprise the tubular parts 49 and the parts 50 which are slidable therein. The parts 50 carry a head 51 which is adapted to engage the caps 52 on the ends of the parts 49, as the arm 27 approaches the position shown in full lines at the left hand side of Fig. 1. When the chute 22 is within the car as shown in dotted lines in Fig. 1 the parts 49 and 50 are relatively arranged substantially as indicated. In moving the chutes through the doorways the part 50 is drawn out of the part 49 until the head 51 engages with the cap 52 and then the lever 46 is drawn from the dotted line position to the full line position and thus effects the withdrawal of the bolt 43 from the notch 42 and permits the bottom 33 to swing to the open position.

The mail bags are piled into the chutes while the chutes are within the car and, by having the chutes relatively tall, space is provided for a large number of bags. When the latches 43 are withdrawn from the notches 42, as just described, the weight of the mail bags will cause the bottoms 33 to drop with considerable force and in order to cushion the bottoms at the end of their movement springs 53 are provided.

On the bottom of the car there are arranged rollers 54 which are engaged by ways 55 on the under side of the bottoms 33, and when the chutes are returned to the interior of the car the engagement of the rollers 54 with the ways 55 causes the bottoms to be returned to the closed position and, when they reach the closed position, the latches 43 are moved into engagement with the notches 42 by means of suitable springs 56 which are secured to the levers 46 as shown in Fig. 1.

Having thus described my invention what I claim is:—

55 1. In apparatus of the class described, the combination of a car, an elevated track therein, a delivery chute suspended therefrom, and means under the floor of the car operatively connected with said chute for moving the same to and fro on said track.

2. In apparatus of the class described, the combination of a car, an elevated track extending transversely of the car in line with a door thereof, a delivery chute having rearwardly extending arms through which

it is suspended from said track, and means under the floor of the car operatively connected with said chute for moving the same to and fro on said track.

3. In apparatus of the class described, 70 the combination of a car, an elevated track extending transversely of the car in line with opposite doors in the sides of the car, a pair of delivery chutes suspended from said track and independently movable thereon, and independent devices under the floor of the car operatively connected with said chutes for moving the same. 75

4. In apparatus of the class described, 80 the combination of a car, an elevated track secured to opposite sides of the car in line with doors in the sides of the car, a pair of delivery chutes having rearwardly extending arms through which the chutes are suspended on said track, said arms permitting 85 the chutes to be projected through said doors, and means under the floor of the car operatively connected with said chutes for moving the same to and fro on said track.

5. In apparatus of the class described, 90 the combination of an elevated track, a delivery chute suspended on said track, a shaft supported below said chute, one or more arms, on said shaft, operatively connected with said chute so as to move the latter to 95 and fro when the shaft is rocked, and means whereby said shaft is rocked.

6. In apparatus of the class described, the combination of an elevated track, a delivery chute suspended on said track, a shaft supported on the car floor, an arm, on said shaft, operatively connected with said chute so as to move the latter to and fro when the shaft is rocked, and means below the car floor whereby said shaft is rocked. 100 105

7. In apparatus of the class described, the combination of an elevated track, a delivery chute suspended on said track and provided with a pivoted dumping bottom, means for latching said bottom in closed position, 110 means for moving said chute on said track, and means for automatically releasing said latching means at a predetermined position of said moving means.

8. In apparatus of the class described, 115 the combination of an elevated track, a delivery chute suspended on said track and provided with a pivoted dumping bottom, means for latching said bottom in closed position, a shaft supported below said chute, 120 arms on said shaft operatively connected with said chute to move the latter on said track, and means, actuated by one of said arms, to release said latching means.

9. In combination with a car having a 125 door, a chute for delivering mail, movable to and fro through the door, a shaft arranged adjacent the door, a plurality of arms on said shaft, means connecting said arms with opposite sides of the chute, means 130

for rocking said shaft, a hinged bottom on said chute, and means whereby said bottom is permitted to swing downwardly independently of the chute when the latter reaches a predetermined point in its outward movement.

10. In combination with a car having a door, a chute, for delivering mail, movable to and fro through said door, means for supporting the chute adapted to prevent the same from tilting when projected from the car, a bottom hinged to the chute, a latch device for normally holding the bottom in closed position, automatically operated means for releasing said latch device, and means for closing the bottom when the chute is moved into the car.

11. In combination with a car having a door, a shaft arranged adjacent the door and having arms thereon, a chute arranged between said arms and operatively connected therewith to be moved to and fro by rocking said shaft, a bottom hinged to the chute, a latch device for normally holding the bot-

tom in closed position, and means connected 25 with one of said arms and said latch device and adapted to automatically release the latch when the chute reaches a predetermined point in its outward movement.

12. In combination with a car having a 30 door, a delivery chute, a shaft arranged adjacent the door, an arm arranged on said shaft and operatively connected with the chute to move the same to and fro when the shaft is rocked, a bottom hinged to the 35 chute, a latch device for normally holding the bottom in closed position, and a telescopic rod connected with said latch device and said arm and adapted to release the latch when the chute reaches a predetermined point in its outward movement. 40

In testimony whereof I affix my signature in presence of two witnesses.

ALBERT HUPP.
